COMBINED COAL DUST AND GAS FIRING SYSTEM

Otto Anschutz, Gummersbach, Rhineland, Germany, assignor to L. & C. Steinmüller G.m.b.H., Gummersbach, Rhineland, Germany

Filed Mar. 22, 1962, Ser. No. 181,697

Claims priority, application Germany, Mar. 25, 1961, St 17,628

6 Claims. (Cl. 110—22)

The present invention relates to coal dust firing systems, and, particularly to firing systems of the stepped type. The heating value of the fuel fired in these firing systems varies considerably, particularly when low-grade bituminous coal is involved.

Inasmuch as for reasons of economy, the firing system has to be designed for a median heating value, conditions can easily occur which, at full load, make it impossible to hold the load. The addition of gas burners frequently fails because the inert gases which develop with the shorter coal dust flames impede the complete combustion of the gases. This is particularly true with all firing systems in which gas flames come into contact with flue gases.

When the gas burners are arranged in an ordinary combustion chamber, there will additionally exist the danger that when being turned off, they are not protected against absorption of radiant heat (Einstrahlung), and when arranged in the side or rear wall, slag.

It is, therefore, an object of the present invention to provide a coal dust firing system, which will overcome the above-mentioned drawbacks.

It is another object of this invention to provide a coal dust firing system in which the combustion of the flue gases of the gas firing system will not be affected by the inert gases.

These and other objects and advantages of the invention will appear more clearly from the following specification in connection with the accompanying drawing diagrammatically illustrating a stepped firing system. The invention, which concerns a melting chamber firing system (Schmelzammerfeuerung) comprising a combustion chamber and, if desired, a post-combustion chamber and radiation chamber, is characterized in that a gas burner equipped combustion chamber is separated from the radiation chamber while the gas exit of said combustion chamber leads directly into the radiation chamber. More specifically, behind the melting chamber proper, i.e., behind the slag catching grate, a separate chamber is provided, separated from the radiation chamber and serving as combustion chamber for the gas firing system. When stepped combustion chambers are employed, the said separate chamber joins, as additional step, the main combustion chamber. The length of said separate chamber depends on the length of the gas flame which, when leaving the gas combustion chamber, is supposed to have substantially burned out.

An embodiment of the invention is illustrated in the following figures, from which:

FIGURE 1 shows a vertical sectional view of a melting chamber firing system with three combustion chambers arranged in a stepped position and a radiation chamber.

FIGURE 2 shows a horizontal sectional view on line plane II—II of FIGURE 1,

FIGURE 3 shows a detail of the slag catching grate in enlarged scale,

FIGURE 4 shows the same detail in side-view,

FIGURE 5 shows a detail of wall 8 in horizontal sectional view in enlarged scale and

FIGURE 6 shows a vertical sectional view of a gas burner combined with an oil burner.

2

Referring now to the drawing in detail, which illustrates an embodiment of the invention in connection with a stepped firing system, the firing system comprises a main combustion chamber 1 equipped with burners 11, and furthermore comprises a combustion chamber portion 2 extending to form a horizontal chamber portion at the bottom of main chamber 1, and equipped with coal dust burners 12. The stepped firing system also comprises a gas burner chamber 3 with gas burners 13. As FIG. 2 shows the gas burner chamber 3 extends over the entire width of the fire chamber and joins the stepped combustion chamber portions 1, 2 as an upper additional step. Similar to the burners of the stepped firing system, the gas burners 13 are arranged in the ceiling of the gas burner chamber 3 so that the gas burner chamber is passed through by the combustion gases in the direction from the top toward the bottom. The gas burner chamber has a bottom exit opening 3a which leads into the radiation chamber 5 directly above the slag catching grate 6, which latter forms the dividing line between the combustion chamber 2 and the radiation chamber 5. In this way, the temperature of the combustion gases leaving the gas burner chamber 3 corresponds approximately to the temperature of the flue gases at said point, which flue gases originated in the stepped combustion chamber. The bottom portion of the firing system is provided with a slag discharge opening 4. As to be seen from FIGS. 3 and 4 the slag catching grate is formed by pipes which merge on the inside with wall 7, separating the main combustion chamber 1 from the gas burner chamber 3 and from the radiation chamber 5. The partition between the gas burner chamber 3 and the radiation chamber 5 is designated with the reference numeral 8.

As illustrated in FIG. 5 this partition is formed by fluid-cooled tubes preferably studded and covered with a layer on the side of chamber 3, while the other side is bare. A combined gas and oil burner 13 is illustrated in FIG. 6. Here the oil nozzle is designated with numeral 14. 15 is the inner tube for core air, 16 the gas channel and 17 the channel for second air. In this way oil and gas may be burned separately or together.

When the firing system according to the invention is in operation, the burners 11 and 12 are turned on in the manner known per se while, when only a slight load is involved, a portion of the burner 11 or all burners 11 may be turned off and only burners 12 are in operation. If, however, the firing system is operated at full load, and if it should occur that the full load cannot be maintained by means of the burners 11 and 12 because of the poorer heating value of the coal being fired at said time, additionally, the burners 13 will be turned on. It is, of course, also possible when operating the firing system below full load, to distribute the load at random over the burners 11, 12 and 13.

When the burners 13 are turned off, a portion of the flue gases passing through the slag catching grate will also flow into the gas burner chamber 3. This part of the flue gases will, however, at the time it reaches the ceiling of the gas burner 13 equipped chamber 3, have cooled to such an extent that burning up of the burner 13 will no longer have to be feared.

If all of the burners are in operation, the dust jets entering through burners 11 and 12 will have sufficient time to burn out until they pass through the slag catching grate 6 and pass into the radiation chamber 5. Similarly, the gas flames of the burners 13 will have burned out completely when they pass from the lower end of the combustion chamber 3 into the radiation chamber 5 and combine with the flue gases from the combustion chambers 1 and 2. Thus, a mutual interference of the com-

bustion by the flue gases of the various combustion chambers, will be practically impossible.

The wall 8, similar to the other wall portions of the radiation chamber 5, consists of evaporator pipes and may be covered at that side which faces the combustion chamber 3.

As will be evident from the above, the present invention yields a number of important advantages:

(a) With melting chamber boilers (Schmelzhammerkesseln) there is obtained the possibility to maintain a great portion of the load by the gas firing system outside the melting chamber, which fact is of particular importance when operating the firing system with coal of a lower heating value.

(b) The distribution of the load is easily controlled over the various combustion chambers.

(c) The fuel gases of the gas firing system engage the coal dust flue gases only when both have burned out, whereby a mutual interference of the combustion by inert gases, will be excluded.

(d) The flue gases leaving the gas burner chamber will, when meeting the coal dust flue gases leaving the post-combustion chamber, have approximately the same temperature as said last-mentioned gases whereby the formation of banks in the radiation chamber and on the post-heating surface, will be avoided.

(e) The gas burners are located so that they are absolutely protected against the absorption of heat by radiation, and also against slagging.

(f) The shifting from one fuel type to another can be effected during the operation of the firing system. Similarly, any desired distribution of the load may be adjusted for coal dust gas burner operation.

(g) The intermediate over-heating can better be held within proper limits than is possible when the gas is blown directly into the melting chamber.

The over-heating can easily be controlled.

It is, of course, to be understood that the present invention is, by no means, limited to the particular construction shown in the drawing, but also comprises any modifications within the scope of the appended claims.

What I claim is:

1. A melting chamber firing system which comprises: means defining a substantially vertical stepped coal dust fired combustion chamber comprising first and second portions each having a ceiling and each having coal dust burner means in the ceiling thereof and each being passed through by the flue gases from the top to the bottom, and means defining a substantially horizontal combustion chamber portion connected at one end to the bottom of said coal dust fired combustion chamber and extending therefrom in the flow direction of the flue gases, means defining a radiation chamber connected to and extending upwardly from the other end of said horizontal chamber portion, a slag collecting grate arranged between said other end of said horizontal chamber portion and said radiation chamber through which said flue gases pass, a slag discharge opening in the bottom of said horizontal chamber portion which is arranged ahead of the slag collecting grate in the flow direction of the flue gases, and means defining a substantially vertical gas fired combustion chamber separate from both said first vertical combustion chamber and said radiation chamber and located therebetween and having a discharge opening at the bottom thereof, said last named means comprising substantially vertical partitions separating said gas fired combustion chamber from said coal dust fired combustion chamber and separating said gas fired combustion chamber from said radiation chamber, and a ceiling having gas

burner means therein, said discharge opening at the bottom of said gas fired combustion chamber leading directly into said radiation chamber at the bottom thereof on the side of said grate opposite said horizontal chamber portion.

2. The arrangement according to claim 1 wherein said gas fired combustion chamber extends to a higher level than said coal dust fired chamber.

3. The arrangement according to claim 2 in which all of said chambers have approximately the same width and extend over the full width of the firing system.

4. The arrangement according to claim 2 in which the cross-sectional area of said first portion of said substantially vertical combustion chamber is smaller at the bottom thereof than at the top.

5. A melting chamber firing system which comprises: wall means defining a coal dust fired combustion chamber in the form of a substantially L-shaped chamber with an upper vertical and a lower horizontal portion, a step in one wall of said vertical portion providing ceiling portions, each ceiling portion being provided with coal dust burners arranged to fire in the direction of the bottom of said vertical chamber portion, and said lower horizontal portion connecting at one end to the bottom of said vertical chamber portion and extending therefrom in the flow direction of the flue gases, means defining a radiation chamber connected to and extending upwardly from the other end of said horizontal chamber portion, a slag collecting grate arranged between said other end of said horizontal chamber portion and said radiation chamber through which said flue gases pass, and means defining a substantially vertical gas fired combustion chamber separate from said L-shaped chamber and said radiation chamber and located therebetween and having a discharge opening at the bottom thereof, said last named means comprising substantially vertical partitions separating said gas fired combustion chamber from said coal dust fired combustion chamber and separating said gas fired combustion chamber from said radiation chamber, and a ceiling having gas burner means therein, said discharge opening at the bottom of said gas fired combustion chamber, leading directly into said radiation chamber at the bottom thereof on the side of said grate opposite said horizontal chamber portion, the ceiling of said gas fired combustion chamber being located at a higher level than that of said coal dust fired combustion chamber.

6. The arrangement according to claim 5 which includes oil burner means in the ceiling of said last named combustion chamber.

UNITED STATES PATENT OFFICE
CERTIFICATE OF CORRECTION

Patent No. 3,188,987

June 15, 1965

Otto Anschütz

It is hereby certified that error appears in the above numbered patent requiring correction and that the said Letters Patent should read as corrected below.

In the grant, line 1, and in the heading to the printed specification, line 4, for "Otto Anschütz", each occurrence, read -- Otto Anschütz --; in the heading to the drawings, Sheets 1 to 3, for "O. ANSCHUTZ", each occurrence, read -- O. ANSCHÜTZ --.

Signed and sealed this 7th day of December 1965.
